(57) **CLAIM**

The ornamental design for a portable, handheld induction heater, as shown and described.

DESCRIPTION

FIG. 1 is a side and top perspective view of a portable, handheld induction heater showing our design;

FIG. 2 is a top perspective view of the portable, handheld induction heater design shown in FIG. 1;

FIG. 3 is a left-side perspective view of the design shown in FIG. 1;

FIG. 4 is a right-side perspective view of the design shown in FIG. 1;

FIG. 5 is a bottom perspective view of the design shown in FIG. 1;

FIG. 6 is a front perspective view of the design shown in FIG. 1; and,

FIG. 7 is a rear perspective view of the design shown in FIG. 1.

In the drawings, the broken lines depict unclaimed subject matter only and form no part of the claimed design.

1 Claim, 4 Drawing Sheets
